UNITED STATES PATENT OFFICE

EARL J. MOBLEY, OF GOLDDENDALE, WASHINGTON

DESIGN FOR A HALL TREE

Application filed May 5, 1927. Serial No. 21,865. Term of patent 3½ years.

To all whom it may concern:

Be it known that I, EARL J. MOBLEY, a citizen of the United States, residing at Goldendale, in the county of Klickitat and State of Washington, have invented a new, original, and ornamental Design for a Hall Tree, of which the following is a specification, reference being had to the accompanying drawing, forming part thereof.

Figure 1 is a side elevation of a hall tree, showing my new design.

Figure 2 is a top plan view.

I claim:

The ornamental design for a hall tree, as shown.

EARL J. MOBLEY.
